UNITED STATES PATENT OFFICE.

WILLIAM M. KELLY, OF NEW YORK, N. Y.

PRINTER'S TYPE.

1,016,224.

Specification of Letters Patent.

Patented Jan. 30, 1912.

Original application filed June 29, 1909, Serial No. 505,063. Divided and this application filed November 16, 1910. Serial No. 592,619.

To all whom it may concern:

Be it known that I, WILLIAM M. KELLY, a citizen of the United States, now residing at New York city, New York, have invented 5 certain new and useful Improvements in Printer's Type, of which the following is a specification, this being a divisional application, the original application having been filed June 29, 1909, Serial No. 505,063, entitled "Type setting and distributing machines."

My invention relates to type for use in type-setting and distributing machines and it is of such a nature that it will permit of 15 the use of various body sizes of type in the same channel, without having to change or adjust the channel in any way.

Referring to the accompanying drawings to which reference will be made in the following description, Figure 1 is a plan; Figs. 2, 3, and 4 are plans of a type channel, such as is adapted to receive and hold set-way, the type shown in Fig. 1—Figs. 3 and 4 showing two different body sizes of type. Fig. 25 5 is a front elevation of a portion of two channels, showing different body sizes contained therein.

I use a plurality of fonts of varying body sizes of type—four different sizes, 1, 2, 3, and 30 4, being shown in Fig. 1. These type, except the minimum size, 1, all have nicks 5. These nicks vary in depth and are in proportion to the body width, so that the remaining "land"—*i. e.*, the distance from the 35 bottom of the nick to the opposite edge of the type (represented in the drawings by the dimension y) is the same in all the sizes and the same as the minimum size.

In Fig. 2 I have shown a type channel 6, 40 such as is adapted to receive my improved type. This channel is provided with block-

ing wards 7, which are adapted to enter the nicks 5 of the type—the type having only a running clearance between the ward 7 and the opposite wall of the channel 6.

I have shown the type with distributing nicks 8 and the channels with corresponding wards 9, in the usual manner; but this has nothing to do with my invention.

In the original application, I illustrated a type-setting machine in which the channels of the magazine cylinder were arranged in sets. One set—say the odd numbered channels—contained one body size of type and the other set—the even numbered channels—55 contained type of a different body size. By turning the magazine slightly, either set could be brought into operative position. In Fig. 5 I have shown, in front elevation, a portion of two channels of such a machine 60 as the one just referred to—one channel 10 containing type of size 3 of Fig. 1 and one channel 11 containing type of size 4.

What I claim is:

1. A plurality of fonts of printer's type 65 of different and various body sizes, nicked so that the remaining "land" is the same in all the various sizes.

2. A plurality of fonts of printer's type 70 of different or various body sizes, the type of maximum body size and the intermediate sizes between the maximum and the minimum body size being nicked so that the remaining "land" is the same as the minimum body size.

In testimony whereof I affix my signature in presence of two witnesses.

WILLIAM M. KELLY.
